INVENTOR.

UNITED STATES PATENT OFFICE.

MERRICK M. BARNES, OF BOSTON, MASSACHUSETTS.

MICROMETER-CALIPERS.

SPECIFICATION forming part of Letters Patent No. 325,233, dated September 1, 1885.

Application filed February 4, 1885. (No model.)

To all whom it may concern:

Be it known that I, MERRICK M. BARNES, of Boston, in the county of Suffolk and State of Massachusetts, a citizen of the United States, 5 have invented certain new and useful Improvements in Micrometer-Calipers, of which the following is a specification.

My present invention relates to micrometer-calipers substantially of the character represented in Letters Patent of mine, No. 271,401, 10 in which a micrometer-caliper is so arranged that it may be moved toward or away from its caliper-anvil.

The object of my present invention is to 15 provide improvements in such devices.

In the drawings, Figure 1 represents, in 20 elevation and partial section, a device embodying my present improvement; and Fig. 2, a vertical section thereof upon the section-line indicated in Fig. 1. Fig. 3 represents the obverse of Fig. 1, and shows more fully the graduation of the shifting-screw.

In the drawings, H represents an arm carrying a micrometer-caliper device, C D, 25 this arm being so arranged that it may be moved toward or away from another arm, H', carrying the anvil. I obtain this motion of the caliper-arm by mounting it upon a shifting-screw, I, a nut, K, being interposed 30 between the arm H and screw I, so that by turning this nut in either direction the desired motion of the arm may be obtained. The arm is prevented from turning by a tail, h, entering a spline on the screw I, as shown. By 35 regulating the pitch of the screw I, and properly graduating it with reference to a zero mark on the nut K, I obtain a convenient device for measuring the precise distance of motion of the arm H.

It is obvious that the arm H might be itself 40 directly threaded upon the screw I; but this construction would involve swinging the arm around the screw, which is often objectionable.

The caliper device shown at C D represents 45 the form shown in my Letters Patent No. 271,401. It is, however, obvious that

other forms of caliper-screw may be substituted for it.

I have also shown and described the graduated shifting-screw only as shifting the caliper-screw relatively to a fixed anvil. It is obvious that the same screw might be arranged to move the anvil relatively to the caliper-screw, the latter remaining stationary. Such a construction, though practically defective, would, nevertheless, embody my present invention to the extent of employing a graduated shifting screw as a means of altering the field of action of a caliper-screw relatively to its opposed caliper-anvil, when either is carried by a movable arm operated by said shifting-screw.

I claim—

1. In a micrometer-caliper of the character herein described, the combination, with the caliper device and its anvil mounted upon standards, either of which is movable relatively to the other, of a graduated shifting-screw adapted to alter at pleasure the field of action of the caliper-screw relatively to its anvil by shifting one of the said standards, all substantially as herein set forth.

2. A micrometer-caliper having its caliper-screw carried upon a shifting-arm and its caliper-anvil mounted upon a fixed arm and provided with a graduated shifting-screw, whereby the shifting-arm may be moved or shifted a regulated distance toward or away from the fixed arm, all substantially as herein set forth.

3. In a micrometer-caliper, the combination of the fixed arm H', carrying an anvil, the movable arm H, carrying a caliper-screw, C, the screw I, nut K, and tail h, all substantially as herein set forth.

In testimony whereof I have hereunto subscribed my name this 29th day of January, A. D. 1885.

MERRICK M. BARNES.

Witnesses:

J. HENRY TAYLOR,
E. B. TOMLINSON.
